(57) **CLAIM**

The ornamental design for a weaving loom, as shown and described.

DESCRIPTION

FIG. 1 is a front, right, top perspective view of a weaving loom, showing my new design;

FIG. 2 is a rear, left, bottom perspective view thereof;

FIG. 3 is a front elevational view thereof;

FIG. 4 is a rear elevational view thereof;

FIG. 5 is a left side view of the enlarged scale thereof;

FIG. 6 is a right side view of the enlarged scale thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 2;

FIG. 11 is an enlarged view of detail 11 in FIG. 3;

FIG. 12 is a perspective sectional view taken along line 12-12 in FIG. 3;

FIG. 13 is an enlarged view of detail 13 in FIG. 4;

FIG. 14 is a front, right, top perspective view of its reduced scale in a detached state;

FIG. 15 is a rear, left, bottom perspective view of its reduced scale in a detached state;

FIG. 16 is a left side view in a detached state;

FIG. 17 is an enlarged view of detail 17 in FIG. 14;

FIG. 18 is an enlarged view of detail 18 in FIG. 15;

FIG. 19 is an enlarged view of detail 19 in FIG. 15; and,

FIG. 20 is an enlarged view of detail 20 in FIG. 15.

The short-short-long dashed broken lines immediately adjacent to the claimed areas in the views represent the boundaries of the design and form no part of the claimed design. The dash-dot-dash broken lines are for notating enlarged views and form no part of the claimed design.

1 Claim, 17 Drawing Sheets
